FIG. 2

FIG. 1

Henry G. Parker

UNITED STATES PATENT OFFICE

171,422

BANANA HOLDING CUP OR SIMILAR ARTICLE

Henry G. Parker, New Orleans, La.

Application August 10, 1953, Serial No. 26,398

Term of patent 7 years

(Cl. D44—9)

To all whom it may concern:

Be it known that I, Henry G. Parker, a citizen of the United States, residing in the parish and city of New Orleans, and State of Louisiana, have invented a new, original, and ornamental Design for Banana Holding Cup or Similar Article, of which the following is a specification, reference being had to the accompanying drawing, forming a part hereof.

Fig. 1 is a perspective view of a banana holding cup or a similar article showing my new design; Fig. 2 is another perspective view thereof with half being omitted for purposes of illustration.

I claim:

The ornamental design for a banana holding cup or similar article, as shown and described.

HENRY G. PARKER.
